(57) **CLAIM**

The ornamental design for a bait rigging system, as shown and described.

DESCRIPTION

FIG. 1 is a front and right perspective view of the bat rigging system showing my new design;
FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof;
FIG. 7 is a bottom plan view thereof; and,
FIG. 8 is a front view of the bait rigging system secured inside the mouth of a dead fish via a zip tie.
The broken line showing a fish and a zip tie in FIG. 8 is included for the purpose of illustrating environmental structure and forms no part of the claimed design.
